Patented June 3, 1969

214,316

CHILD'S CHAIR

Everett Stacy Dukes, 5010 E. Broadway,
Long Beach, Calif. 90803

Filed Apr. 1, 1968, Ser. No. 11,250

Term of patent 7 years

Int. Cl. D6—01

U.S. Cl. D15—1

FIG.1

FIG.5

FIG. 1 is a perspective view of a child's chair showing my new design;

FIG. 2 is a front elevational view of said chair;

FIG. 3 is a side elevational view of said chair;

FIG. 4 is a rear elevational view of said chair; and

FIG. 5 is a top plan view of said chair.

I claim:

The ornamental design for a child's chair, substantially as shown.
